AIR COOLED AIR COMPRESSOR

Arthur C. Eaton, Mount Pleasant, Mich.

Application December 21, 1951, Serial No. 262,748

14 Claims. (Cl. 230—20)

1

This invention relates to a novel form of air cooled air compressor of the rotary type including an encased revolving rotor by means of which air is compressed for supplying a storage tank with compressed air or for supplying air to other devices operated by compressed air and wherein the air is initially utilized by the compressor due to the rotary movement of the rotor for cooling said rotor and the parts carried thereby.

Another object of the invention is to provide an air compressor having a revolving rotor functioning similarly to a flywheel and having cam actuated compressing means carried thereby and actuated by the rotation thereof for compressing air as the rotor is revolved.

Another object of the invention is to provide an air compressor wherein the air is supplied under pressure to the compressing means eliminating the necessity of drawing the air by vacuum thereto thus increasing the capacity of the compressing means, due to the fact that the air is under pressure at the commencement of the compression stroke.

A further object of the invention is to provide a novel cam means for actuating the air compressing means and which is adjustable automatically in response to the air pressure within a tank or container supplied by the compressor to cause the cam means to assume an inoperative position to prevent operation of the compressing means when the pressure in the storage tank reaches or exceeds a maximum capacity.

A further object of the invention is to provide a compressor having novel means responsive to an excess pressure of air in a storage tank automatically rendering the compressor inoperative until the air pressure in the storage tank is diminished.

Still a further object of the invention is to provide an air compressor having a novel lubricating means to maintain its supply of lubricant under pressure to the moving parts thereof at all times while the compressor is in operation.

Various other objects and advantages of the invention will hereinafter become more fully apparent from the following description of the drawings, illustrating presently preferred embodiments thereof, and wherein:

Figure 1 is a longitudinal central sectional view, partly in side elevation illustrating one preferred embodiment of the invention;

Figures 2, 3 and 4 are cross sectional views thereof taken substantially along planes as indicated by the lines 2—2, 3—3 and 4—4 of Figure 1, Figure 4 being on a reduced scale;

2

Figure 5 is an enlarged fragmentary longitudinal sectional view of a portion of the compressor;

Figure 6 is an enlarged end elevational view of a portion of the compressor;

Figure 7 is an enlarged fragmentary longitudinal sectional view partly in elevation of one of the compressor pistons;

Figure 8 is an end elevational view thereof 10 looking from left to right of Figure 7;

Figures 9 and 10 are cross sectional views of the piston rod and piston, respectively, taken substantially along planes as indicated by the lines 9—9 and 10—10, respectively, of Figure 7;

Figure 11 is a view similar to Figure 4 looking toward the inner side of the cam end of the compressor casing showing one modified form of cam structure;

Figure 12 is a vertical sectional view taken substantially along a plane as indicated by the line 12—12 of Figure 11;

Figure 13 is an enlarged fragmentary plan view of a portion of one of the cam elements;

Figure 14 is an end elevational view thereof as viewed along the line 14—14 of Figure 13;

Figure 15 is a view similar to Figure 11 illustrating another modified form of variable cam;

Figure 16 is a cross sectional view thereof taken substantially along a plane as indicated by the line 16—16 of Figure 15;

Figure 17 is a view similar to Figure 15 illustrating still another form of variable cam;

Figure 18 is a sectional view thereof taken substantially along a plane as indicated by the line 18—18 of Figure 17;

Figure 19 is a view in the same plane as Figure 18 but showing the cam in an elevated, operative position as distinguished from its inoperative position as illustrated in Figure 18;

Figure 20 is a top plan view of one element of 40 the cam of Figures 17, 18 and 19;

Figure 21 is an edge elevational view thereof, and

Figure 22 is a fragmentary side elevational view showing one form of a pressure actuated 45 switch for use with the cam structure of Figures 1 to 10.

Referring more specifically to the drawings, first with reference to Figures 1 to 10, the novel compressor in its entirety is designated generally

50 25 and includes a casing or housing, designated generally 26 which is composed of a side wall 27, which is preferably cylindrical, and end walls 28 and 29. The side wall 27 is provided with depending foot members 30 on which the housing 26 is adapted to rest and which may be suitably

secured to a supporting surface, not shown, for maintaining the casing 26 stationary.

A stationary shaft 31 extends inwardly through the central portion of the end wall 28 and terminates intermediate of the ends of the casing 26 and is disposed axially thereof. Said stationary shaft 31 being provided with a head 32 at its outer end to secure it to the outer side of the end wall 28 by a suitable fastening 33. A rotor, designated generally 34 is journaled on the stationary shaft 31 and is disposed for rotation in the casing 26, the bore 35 of said rotor which turnably engages the shaft 31 being provided with enlarged ends 36 and 37 to accommodate tapered antifriction bearings 38 and 39, respectively, which are disposed therein and in engagement with the shaft 31. The bearing 39 which is located adjacent the head or end 28 abuts against an adjustable collar 40 secured to the shaft 31 to prevent the rotor 34 from sliding toward said end 28.

A driven rotary shaft 41 extends axially into the casing 26 through the end wall 29 and is journaled therein by a tapered antifriction bearing unit 42 which seats in an inwardly opening recess 43 of the wall 29. The wall 29 on its outer side is provided with a stuffing box 44 surrounding a portion of the shaft 41. The shaft 41 is provided with an enlargement 45 which bears against the bearing 42 to prevent the shaft from being displaced outwardly through the wall 29. The inner flanged end 46 of the shaft 41 is secured by fastenings 47 to one end of a coupler 48, the opposite end of which is secured by fastenings 49 to the end of the rotor 34 in which the anti-friction bearing unit 38 is mounted, so that the collar 40 and enlargement 45 combine to prevent sliding movement of the rotor 34 in either direction on the stationary shaft 31 and the bearing units 39 and 42 form thrust bearings which are engaged by the collar 40 and enlargement 45, respectively.

The rotor 34 has an annular outwardly extending flange 50 located adjacent the end of its central or hub portion 51 in which the recess 37 is formed and which flange 50 is provided adjacent its periphery with an annular flange 52 which projects at a right angle to the plane of the flange 50 and toward the end wall 29. The flange or wall 50 and the annular peripheral flange 52 of the rotor 34 combine to form an annular chamber 53 surrounded by the peripheral flange 52 and which is disposed between said flange and the opposite end of the hub 51, which is secured to the coupling 48. Said annular chamber 53 opens toward the end wall 29. The peripheral flange 52 is provided with two diametrically opposed internal enlargements 54 on its inner side which are disposed within the chamber 53, forming cylinders 55 which open toward the end wall 29. The outer surface of the peripheral flange 52 and the contiguous peripheral edge of the wall 50 are provided with spaced annular ribs or enlargements 56 and 57 extending therearound. A ring 58 which is relatively wide radially fits on the peripheral edge of the wall 50 with a portion of one side thereof which is located adjacent its inner edge abutting against the adjacent side of the annular rib 56 and to which the ring 58 is secured by circumferentially spaced fastenings 59. If desired, the ring 58 may be formed integral with the wall 50. The outer side of the wall 50, the outer

outer side of the ring 58 are each preferably provided with cooling fins 60.

A plurality of corresponding vanes 61 are mounted on the shoulders 56 and 57 in circumferentially spaced relationship to one another, each of said vanes 61 being curved in the same direction from its inner to its outer edge and having an arcuately bowed flange projecting from the convex side of its inner edge and which is likewise arcuately bowed transversely. Said flanges 62 have their end portions resting on the shoulders 56 and 57 and the flange 62 of each vane 61 extends to adjacent the concave side of the next trailing vane 61 to provide a restricted slot 63 therebetween. Each of the flanges 62 is connected to each of the shoulders 56 and 57 by at least one fastening 64. The flanges 62 combine with the shoulders 56 and 57 and with the portion of the exterior surface of the annular peripheral flange 52, located between said shoulders, to form an annular chamber having the outwardly opening slots 63 and which is provided with two inwardly extending passages 65 which extend inwardly from said annular chamber 66 and one of which opens into an annular internal enlargement 67 of each of the cylinders 55. A second relatively wide ring 68 is disposed on the outer end of the outer surface of the peripheral flange 52 and against the outer side of the other shoulder 57 and said rings 58 and 68 extend outwardly to the outer edges of the vanes 61 and to adjacent the inner surface of the cylindrical wall 27 and combine with said vanes to form air scoops for deflecting air inwardly through the slots 63 into the annular chamber 66, when the rotor 34 is revolved in a direction so that the outer edges of the vanes 61 constitute their leading edges, or counterclockwise as seen in Figure 2. It will likewise be readily apparent that the vanes 61 may be secured in reversed positions to function in the same manner when the rotor is revolved in the opposite direction or clockwise as seen in Figure 2.

As illustrated in Figures 1, 2 and 4, the cylindrical wall 27 is provided with spaced annular external ribs 69 on which is disposed an annular band or strip 70 which is secured by fastenings 71 adjacent the side edges to the peripheries of the ribs 69 to combine therewith and with the portion of the cylindrical wall 27 which said band surrounds to form an annular outer air chamber 72. Said wall portion is provided with a plurality of circumferentially spaced longitudinally extending slots 73 which communicate with the chamber 72 and which open into the interior of the casing 26 between the rings 58 and 68. The band 70 is preferably provided with two air inlet conduits 74 which open downwardly into the chamber 72, as best illustrated in Figure 2, each of which is preferably provided at its upper inlet end with an air filter 75 for filtering the air entering the casing 26.

The stationary shaft 31 is provided with an annular groove 76 in its periphery which is connected by radial passages 77 to one end of a longitudinal passage 78 of the shaft 31, and the opposite end of which opens outwardly through the head 32 and is in communication with a conduit 79 which is tapped into said end of the passage 78. The conduit 79 is adapted to communicate at its opposite end with any suitable air storage tank 80, such as illustrated in Figure 22 or with any other suitable device adapted to be supplied with or operated by compressed air.

cylinders 55 are provided with restricted seats 81 at their inner ends which open into cavities 82 formed in the rotor wall 50, each of which cavities has a bore 83 extending radially inward therefrom into the hub bore 35 and which communicates with the groove 76. A valve housing 84 has an enlarged flanged end 85 seating in each seat 81 and projects therefrom into the adjacent cavity 82. Each housing 84, as best seen in Figure 5, has a bore 86 extending longitudinally therethrough provided with an enlarged externally threaded outer end 87 which opens into the cavity 82 and a restricted inner end 88, defining a valve seat which opens into the cylinder 55. A perforated valve stem guide and spring seat 89 is threaded into the bore end 87 to slidably guide the stem 90 of a valve 91 which seats in the valve seat 88 and against which bears an end of a spring 92 mounted on the stem 90 and having its opposite end abutting the seat guide 89.

Each cylinder 55 has a liner or sleeve 93 disposed therein which abuts a portion of the housing head 35 in the same cylinder for retaining said head against the seat 81. Each sleeve 93 is provided with a series of circumferentially spaced openings 94 which open into the groove 67. A piston 95 is reciprocally mounted in each sleeve 93 and has a piston rod 96 extending therefrom reciprocally through a guide 97 which is provided with a flanged head 98 which closes the open end of its associated cylinder 55 and which is secured by fastenings 99 to the end of the enlargement forming said cylinder. The heads 98 likewise retain the sleeves 93 in seated positions and tightly against the housing head 35.

As seen in Figure 1, an annular internal wall 109 is secured in liquid tight engagement around a part of the inner surface of the cylindrical wall 27 between the rotor 34 and end wall 29. The inner edge of the wall 100 is spaced a substantial distance from the longitudinal center of the casing 26. The guides 97 are provided with grooves 101 which fit the inner edge of the wall 100. The bottom portions of the walls 29 and 100 combine to form a sump or storage chamber for oil, as seen at 102 in Figure 1. It will also be noted that portions of the guide heads 98 overlie the outer surface of the peripheral flange 52 and abut against the outer side of the ring member 66 to retain said ring member on the flange 52 and against the outer side of the rib 57.

Each piston rod 96 is provided with a wheel fork 103 at its opposite end in which is journaled a wheel or roller 104 which is disposed to ride on the inner surface of the wall 29 in a circular path when the rotor 34 is revolved and said wall 29 is provided on its inner side in the path of travel of the rollers 104 with two arcuately or circumferentially extending cam grooves 105 the beds of which are inclined upwardly and toward the inner surface of the wall 29 in a counterclockwise direction from end-to-end thereof so that as the rollers 104 travel about the inner surface of the wall 29, each roller in moving counterclockwise will simultaneously be displaced by a spring 106 into the deep end of a cam groove 105 and in traveling counterclockwise will roll up the inclined bed of said groove back onto the surface of the wall 29, each roller 104 engaging each cam groove 105 during each revolution thereof to cause each of the pistons 95 to make two complete strokes in each revolution of the rotor 34. The springs 106 are mounted on the

piston rods 96 between the outer ends of the guides 97 and the forks 103.

Each piston rod 96, as best seen in Figure 7, is threaded into one end of a bore 107 which extends through the piston 95 and said piston rod carries a lock nut 108 which is threaded thereon and abuts against the outer end of the piston. The opposite end of the bore 107 is provided with a valve seat 109 for an outwardly opening valve 110 which seats thereagainst and has a valve stem 111 extending inwardly of the bore 107 from the valve 110 through a perforated guide 112 in which said stem is reciprocally mounted for guiding the movement of the valve 110. The guide 112 is threaded into the bore 107 between the valve seat 109 and the adjacent end of the piston rod 96. An expansion spring 113 carried by the valve stem 111 normally retains the valve 110 in a seated position. The piston 95 is provided with a plurality of air passages 114 which open into the intermediate portion of the bore 107 and outwardly of the rear face of the piston 95. The periphery of the piston 95 is provided with spaced piston rings 115.

A gear 116 is disposed around the end of the hub 51 located adjacent the coupling 48, and is preferably formed integral therewith and meshes with a pinion 117 fixed to a shaft 118 which drives a pump 119. The pump 119 is disposed between the rotor 34 and end wall 29, adjacent the axis of the casing 26 and is supported by a bracket 120 secured to the inner side of the end wall 29. An inlet conduit 121 has an inlet end opening into the sump or oil reservoir 102 through the cylindrical wall 27 and has an opposite end tapped into the inlet side of the pump 119, said conduit 121 having a portion disposed externally of the casing 26, as illustrated in Figure 1, and including a bore 122 extending through the wall 29. An outlet conduit 123 has one end tapped into the outlet side of the pump 119 and has its opposite end tapped into the stationary shaft head 32 and communicating with a passage 124 which extends longitudinally of said head and of the shaft 31. The conduit 123 extends along the underside of the casing 26 and along portions of the ends thereof, as seen in Figure 1, and includes a bore portion 125 extending through the end wall 29, adjacent the bearing 42 and has a branch port 126 opening into and lubricating the bearing 42. The annular groove 76 of the shaft 31 is located between two annular grooves 127, formed in a periphery of said shaft 31, each of which contains a plurality of split rings 128, the split portions of which are disposed out of registry to provide a substantially solid annular band or ring. The lubricating passage 124 has branch ports 129 for lubricating the rings of each groove 127 and a branch port 130 for lubricating the other thrust bearing 39. The other end of the passage 124 opens into an annular groove 131 in the periphery of the shaft 31 which is located adjacent the bearing 38 and which groove communicates with radial ports 132 of the hub 51, to each of which is connected an end of a lubricating conduit 133. The opposite ends of the conduits 133 are tapped into the outer ends of radial passages 134, as best seen in Figures 1 and 5, the inner ends of which passages lubricate the bores of the guides 97, in which said passages are formed for lubricating the piston rods 96. As seen in Figure 7, each piston rod 96 has a longitudinally extending lubricating passage 135 including a radial branch passage 136 by means of which the

lubricant 102 is supplied to the passage 135 from the passage 134 of the guide 97 in which said piston rod 96 is reciprocally disposed. One end 137 of the passage 135 lubricates the wheel or roller 104 which is carried by the piston rod 96 containing said passage 135, and the opposite, radially disposed end 138 of each passage 135 opens into a lubricating passage 139 of the piston 95, to which the connection rod 96 is connected. Each passage 139 has an outer end opening outwardly of the periphery of the piston 95 between its rings 115 for lubricating the periphery of the piston which engages the sleeve 93. From the foregoing it will be readily apparent that when the rotor which with the vanes or scoops 61 forms a turbine wheel, is revolved, the pump 119 will be actuated for pumping oil 102 from the reservoir as seen in Figure 1 through the pipes or conduits 121 and 123, through the passage 124 and conduits 122 for lubricating the rotor bearing and other parts of the rotor which engage the stationary shaft 31 and for also lubricating the pistons 95, piston rods 96 and the wheels or rollers 104.

Assuming that the drive shaft 41 is being revolved as by means of an electric motor, not shown, it will be readily apparent that the rotor turbine wheel 34 will be rotated at the same speed as said drive shaft by being connected thereto by the coupling 43 and will turn on the stationary shaft 31. As said turbine wheel is revolved, the vanes or scoops 61 turning counterclockwise as seen in Figure 2 will create a suction in the outer annular chamber 72 to cause air to be drawn into said chamber through the air intakes 74 provided with the filters 75. The air will be drawn from said annular chamber 72 by the scoops 61 inwardly through the ports 73 into the turbine wheel pockets formed by the vanes or scoops 61 and the rings 58 and 63. The air impinging against the forward, concave sides of the scoops 61 will be deflected inwardly through the restricted slots 63 into the inner annular air chamber 66 in which chamber the air will be compressed and forced under pressure radially inwardly through the passages 65 into the annular grooves 67 of the two cylinders 54 from which the air will escape under pressure through the sleeve openings 94 into the interior of the sleeves 93.

As the turbine wheel 34 is revolving to thus charge the cylinder sleeves 93 with compressed air, the wheels or rollers 94 will be riding the inner surface of the end wall 29, as best seen in Figure 3, in a counterclockwise direction and as each roller 94 reaches each of the cam grooves 105 it will be projected by its spring 106 into the bed of said groove at its deepest end, thereby allowing the two springs 106 to simultaneously move the pistons 95 to their retracted positions of Figure 1 adjacent the guides 97 and so that the openings 94 will be exposed to the left of the pistons 95 for fully charging the cylinder sleeves 93 between the pistons 95 and the cylinder heads 85. As the turbine wheel continues to turn counterclockwise, the rollers 104 will ride up the inclined bottoms of the cam grooves 105 and during their initial travel therealong, the pistons 95 will be displaced to the left for initially closing the ports or openings 94 and for thereafter further compressing the air between the pistons and cylinder heads 85. This will cause the valves 91 to be opened to allow the air to escape through the bores 86 and guides 89 into the cavities 82, through the radial pas-

5 sages 85 into the annular groove 76 of the shaft 31 thence through the passages 77 into the passage 78. The compressed air will pass through the passage 78 and conduit 79 into the storage tank 80, as seen in Figure 22. As each piston 95 moves to the left past the openings 94, additional air will be forced into the sleeves 93 behind or to the right of the pistons 95, as previously described, to fill said sleeves with compressed air 10 to the right of the projected pistons 95. When the rollers 104 have completed a half revolution and each drops into the other cam groove 105, the pistons 95 will again be retracted by the springs 106 and return to their positions of Figure 1 and in so moving from left to right, the compressed air to the right of the pistons will 15 flow from right to left through the passages 114 and bores 107, and through the guides 112 to unseat the valves 110 to allow the compressed air 20 to escape to the opposite or left hand side of each piston. The cylinder sleeves will thus be initially charged with air during substantially the entire return stroke of each piston and will be further charged with compressed air as the 25 pistons pass to positions to the right of the openings 94, as previously described. It will be understood that each piston 95 executes two compression strokes and two return strokes for each revolution of the turbine wheel 34. If desired, it 30 will be readily apparent that four equally spaced cylinders and pistons can be provided in lieu of the two cylinders 54 and two pistons 95 and in which case either two or four cams 105 could be provided, depending upon the amount of air required; however the two compressor cylinders with the two cams is equal to a four cylinder compressor and is capable of compressing more air than a four-cylinder compressor having cylinders of the same size due to the compressing 35 of the air in the cylinders on the backstroke of the pistons rather than having air drawn into the pistons by suction, as is conventional and which causes a vacuum to exist in the conventional cylinder as the piston thereof starts its 40 compression stroke.

45 Any suitable automatic switch means may be utilized for de-energizing the electric motor by means of which the shaft 41 is driven, as for example, the diaphragm switch 146 as illustrated 50 in Figure 22 which is connected to the storage tank 80 so that when an air pressure exists in said tank above a predetermined, safe pressure, the air impinging on the diaphragm of the unit 49 will cause the rod 141 to swing the arm 142 55 upwardly on its pivot 143 to thereby elevate the connecting rod 144 to thus swing the switch arm 145 upwardly to move the switch 146, which is adapted to be interposed in the circuit of the electric motor, not shown, to a circuit interrupting position. The electric motor will thus 60 be de-energized to stop operation of the turbine wheel 34 until the pressure in the tank 80 diminishes sufficiently so that the adjustable weight 147 will swing the lever 142 downwardly 65 and cause the switch arm 145 to be swung downwardly and back to a circuit closing position of the switch 146 to thereby again energize the electric motor for driving the turbine wheel 34.

70 The shaft 41 may also be driven by other means not capable of being started and stopped by the switch 146, as for example, a gasoline or diesel engine, not shown, in which case another type of cam may be utilized to prevent the building up of too great an air pressure in the 75 storage tank, as for example the cam means as

illustrated in Figures 11 to 14 comprising an annular groove 147 formed in the inner side of the end wall 29a in which are positioned a pair of corresponding oppositely disposed cam tracks, designated generally 148, each including two arcuately curved strips 149 having adjacent ends which are connected by a hinge 150. Said cam strips 149 have remote ends which slidably engage portions of the bed of the groove 147 and are provided adjacent said remote ends with crossarms 151 which extend into undercut inwardly opening grooves 152 which are formed in the upright side walls of the groove 147 and which open into the sides of said groove. A pin 153 extends upwardly through each arm 151 and is reciprocally mounted therein and has a roller 154 journalled in its upper end, which rollers engage the top walls of the grooves 152 and are yieldably urged upwardly into engagement therewith by springs 155 which are carried by the pins 153 and urge said pins and rollers upwardly. The pin 156 of the hinge 150 has an outer end which extends into another recessed portion 157 of the end wall 29a and on which is swingably mounted one end of a lever 158 on the opposite end of which is journalled a shaft 159. A roller 160 is journalled on the outer end of the shaft 159 and engages a groove 161 formed in the outer wall of the recess 157. A link 162 is likewise connected to the shaft 159 and to one end of a pull spring 163 which is anchored to the wall 29a at its opposite end at 164. It will be readily apparent that the spring 163 will exert a pull on the lever 158 to cause the roller 160 to travel toward said spring for swinging the lever 158 toward an upright position to elevate the hinged intermediate portion 150 of the cam track 148 so that the rollers 164 will pass over each of the cams 149 during each revolution of the turbine wheel 34 to execute a pumping operation in the same manner as previously described in reference to the form of the invention as illustrated in Figures 1 to 10.

A cylinder 165 has an open end which is fastened to the outer side of the wall 29a and contains a piston 166 having a piston rod 167 which extends slidably through a stuffing box 168 mounted in the end wall 29a. The opposite end of the piston rod 167 is connected to the opposite end of the hinge pin 156. A spring 169 carried by said piston rod urges the piston rod inwardly of the wall 29a. The storage tank 80a is provided with a blowoff valve 170 which opens into a housing 171 which is connected to the inner portion of the cylinder 165 by a conduit 172 and which is additionally provided with a vent port 173. When the air pressure becomes excessive in the tank 80a it will overcome the pressure of the spring 170a to open the relief valve 170 allowing the air to escape through the conduit 172 into the cylinder 165 between the stuffing box 168 and the piston 166. The piston 166 will thus be forced by the compressed air toward the outer end of the cylinder 165 and the piston rod 167 will exert a pull on the hinge pin 156 against the action of the springs 153 and 169 to draw the hinged ends of the cam sections 149 outwardly of the end wall 29a to position said sections 149 with their ends more nearly in the same plane thereby reducing the angle or pitch of the track sections 149 to thus minimize the extent that the pistons 95 will be actuated by said cam to thereby reduce or totally eliminate the pumping operation of the pistons 95. It will be understood that each cam 148 is

provided with all the structure previously described and that both cams are increased or decreased in pitch simultaneously. A limited amount of air will escape from the housing 171 through its vent aperture 173 and as the pressure in the tank 80a diminishes, as by utilizing a part of the air therein, the air will escape from the cylinder 165 through the vent 173 and the spring 169 cooperates with the spring 163 to urge the track sections 149 back toward the maximum pitch position for increasing the length of the strokes of the two pump pistons 95 and accordingly the amount of air which will be pumped thereby.

Figures 15 and 16 illustrate another form of variable cam and wherein the end wall 29b is made relatively thin and is provided with two diametrically spaced supports 174 which project from its inner side and which support the ends of two cam tracks, each designated generally 175 and each of which is substantially semicircular. Each cam track 175 is formed of two corresponding sections 176 the adjacent ends of which are connected by hinges 177, a pin 178 of which extends outwardly of the outer edges of the sections 176 and is secured to one end of a lever 179. A connecting rod or link 180 is pivotally connected at 181 to the opposite end of the lever 179 and has a free end fastened to one end of a pull spring 182 which is anchored at its opposite end by a pin 183 to the wall 29b and which urges the lever 179 to swing in a clockwise direction, as seen in Figure 16 with its last-mentioned end sliding and fulcruming on the wall 29b for urging the hinged ends of the sections 176 inwardly and while the opposite, free ends slide on the supports 174 for causing the cam track sections 176 to assume elevated operative positions, as illustrated in dotted lines in Figure 16.

A cylinder 165b containing a piston 166b and a connecting rod 167b is supported on the outer side of the wall 29b in the same manner as the cylinder 165, previously described, and said piston rod extends inwardly through the wall 29b and is pivotally connected to a downwardly offset intermediate portion 172b of the hinge pin 178. The piston rod 167b carries a spring 169b that also urges the piston rod and piston inwardly of the wall 29b for urging the cam track sections 176 to their dotted line positions of Figure 16. Air under pressure is supplied to the cylinder 165b inwardly of the piston 166b by a conduit 172b which is connected to a storage tank, not shown, corresponding to the storage tank 80a by a blowoff valve unit, not shown, corresponding to the unit as illustrated in Figure 12, so that the pistons 166b of the two cylinders 165b will move the sections of the two cam tracks 175 into coplanar full line positions as illustrated in Figure 16 when an excessive air pressure exists in the tank to which the conduits 172b are connected, so that the rollers 164 engaging said cam tracks will not be displaced away from the end wall 29b, in order that the pistons 95 will not reciprocate when the storage tank is fully charged with compressed air.

Figures 17 to 21 illustrate another form of variable cam tracks including an end wall 29c having parallel cam track receiving recesses 184 the side walls of which are provided with inwardly opening grooves 185 for receiving plates 186, the side edges of which are slidably mounted in said grooves for movement toward and away from one another and are urged toward one an-

other by expansion springs 187. A cylinder 165c, piston 166c and piston rod 167c form a unit corresponding to the piston, cylinder and piston rod units of Figures 12 and 16 and wherein the piston rod is urged inwardly of the wall 29c by a spring 169c, it being understood that one of said units is associated with each groove 184. However, the inner end of the piston rod 167c bears against the intermediate portion of a rigid inverted V-shaped cam track 188, the apex of which is normally disposed beneath and between the adjacent ends of the plates 186, when the cams are in inoperative positions, as illustrated in Figure 18. A lever, link and spring unit 179c, 180c and 182c, respectively, similar to the unit of Figures 15 and 16 is connected to a rod or shaft 178c which projects laterally from the upper end of each piston rod 167c and said lever, link and spring units are disposed in separate recesses 189 of the wall 29c which open into the outer sides of the recesses 184 and each of which has an outer wall containing a guide groove 190 for an extension of an end of the pin 181 connecting each lever 179c and link 180c, so that said unit can be urged with the piston and piston rod inwardly, in combination with the spring 169c for urging the cam track 188 to a projected, operative position as illustrated in Figure 19. The plates 186 are provided with rollers 191 on their inner sides, near their adjacent ends by means of which said plates are spread away from one another against the action of the springs 187 when the cam tracks 188 are moved to projected positions as illustrated in Figure 19 by the springs 169c and 182c, so that the rollers 191 at each revolution of the turbine wheel 34 will ride over each of the two sets of plates 186 and over the inclined surfaces of each of the cam tracks 188 to cause each of the pistons 95 to complete two strokes at each revolution of the turbine wheel 34. The cam tracks 188 are moved to retracted positions by air entering the cylinders 165c inwardly of the pistons 166c through conduits 172c, all in the same manner as previously described and as fully illustrated in Figure 12, so that when a storage tank, not shown, is fully charged with compressed air the cam tracks 188 will be in retracted positions as illustrated in Figure 18 to cause the rollers 191 to ride over the plates 186 and the inner surface of the wall 29c without being displaced longitudinally of the turbine casing sufficiently to pump air from the cylinders 55 through the cylinder heads 84.

In order to insure that the rollers 191 will be disposed for rolling engagement at all times either with an inclined cam surface or a flat surface, each fork 193 is secured nonrotatably to its piston rod 96 by a setscrew 192. Additionally, the piston rods 96 are provided with flat portions 193 so that the piston rods are of noncircular cross section, as best seen in Figure 9, for slidably and nonrotatably engaging bores 194 in the guide heads 97 which are of noncircular cross section, as best illustrated in Figure 6. Each flat surface 193 extends to the outer end of its piston rod 96 so that the piston rods may be inserted through the bores 194 before the forks 193 are secured thereto. By this construction, the oil passages 136 will always be properly positioned to move into registry with the oil passages 134.

Various other modifications and changes are contemplated and may obviously be resorted to, without departing from the spirit or scope of the invention as hereinafter defined by the appended claims.

I claim as my invention:

1. A rotary type air compressor comprising a casing having first and second end walls and a cylindrical side wall, a stationary shaft secured to one of said end walls and extending axially into and partially through the casing, a driven rotary shaft extending axially into the casing through the other second end wall and journaled therein, a rotor journaled on the stationary shaft for rotation within the casing and coupled to said driven shaft and rotated thereby, a turbine unit secured around the periphery of the rotor for rotation therewith within the casing and extending outwardly therefrom to adjacent the cylindrical wall of the casing and including a plurality of circumferentially spaced vanes forming scoops having leading outer edges disposed in advance of their trailing inner edges, said cylindrical casing wall having air inlet ports adjacent said turbine unit through which air is drawn into the casing from pockets of the turbine unit formed between the vanes thereof by rotation of the rotor, cylinders formed in said rotor and disposed longitudinally thereof between the turbine unit and the stationary shaft, said rotor being provided with air passages leading from the pockets of the turbine unit to said cylinders, said rotor and stationary shaft having communicating passages extending from corresponding ends of said cylinders and opening outwardly of an outer end of the stationary shaft, pistons reciprocally mounted in said cylinders having piston rods extending therefrom away from the last mentioned rotor passages and toward the second casing end wall, spring means carried by said piston rods for urging the piston rods and pistons toward said second end wall, and cam means associated with the second end wall engaging said piston rods for intermittently displacing the piston rods and pistons toward the last mentioned rotor air passages for compressing air in the cylinders and forcing the compressed air through the last mentioned rotor passages into the stationary shaft passage, said turbine forcing air under pressure into said cylinders in certain positions of the pistons relatively to the cylinders whereby the pistons on their compression strokes will initially operate on air partially compressed in said cylinders.

2. A rotary type compressor as in claim 1, said rotor and turbine unit being cooled by the air drawn into the casing by the turbine unit and expelled inwardly therefrom into said cylinders, said rotor having an annular air chamber surrounding a portion of its periphery communicating with the first mentioned rotor passages and opening into the turbine unit pockets in which the air is compressed and propelled circumferentially of the rotor to the first mentioned rotor passages for cooling the peripheral portion of the rotor.

3. A rotary type air compressor as in claim 1, said first mentioned passages opening into the cylinders remote from said cylinder ends and being closed by the pistons during the initial movements thereof from retracted positions, remote to the cylinder ends, toward said cylinder ends.

4. A rotary type air compressor as in claim 3, each of said first mentioned passages including an annular inner portion formed in the cylinder bore, each of said cylinders including a sleeve in which the piston is reciprocally mounted having a plurality of circumferentially spaced ports extending radially therethrough and commu-

13

nicating with the annular portion of the first mentioned air passage of said cylinder.

5. A rotary type compressor as in claim 4, guide members detachably secured to and closing the opposite ends of said cylinders through which the piston rods reciprocably extend, each of said pistons having a passage extending therethrough provided with a check valve opening toward the cylinder head whereby the air forced under pressure into the cylinders between the pistons and guide members will pass through the pistons toward the cylinder heads during the movement of the pistons toward the guide members for charging the cylinders with compressed air on the return strokes of the pistons.

6. A rotary type air compressor as in claim 5, and lubricating means for lubricating the rotor, pistons and piston rods including a rotary pump mounted in a stationary position within the casing and driven by the rotor, a lubricant reservoir formed in a portion of the casing and connected to the pump intake, and a conduit leading from the pump outlet having branch passages for lubricating the driven shaft, rotor, pistons and piston rods.

7. A rotary type compressor as in claim 6, said outlet conduit of the pump including a passage extending longitudinally of the stationary shaft and an annular groove formed in a portion of the periphery of the stationary shaft.

8. A rotary type air compressor as in claim 1, the periphery of said rotor being provided with longitudinally spaced annular ribs on which said turbine vanes are mounted and secured, said turbine unit including ring members mounted on the periphery of the rotor against the remote sides of said annular ribs and extending outwardly therefrom to the outer, leading edges of the vanes.

9. A rotary type compressor as in claim 8, said turbine vanes each having a flange at its inner edge extending circumferentially therefrom to adjacent the inner edge of the next trailing vane and combining therewith to form a narrow passage between pockets formed by the adjacent turbine vanes and turbine rings and the annular air chamber formed between the rotor periphery, the vane flanges and said rotor ribs.

10. A rotary type air compressor as in claim 1, said second end wall having at least one arcuately extending recess on its inner face provided with a bed portion inclined from end-to-end thereof forming a cam groove constituting a part of said cam means, and rollers journaled on the ends of the piston rods located remote to the pistons for engaging the cam groove bed on the inner face of the second end casing wall.

11. A rotary type air compressor as in claim 1, a roller journaled on each of the piston rods, said cam means including a plurality of circumferentially spaced cam tracks movably supported by said second end casing wall for movement toward and away from the rotor, spring means for urging said cam tracks toward the rotor and into operative positions, each of the cam tracks having inclined surfaces disposed to be engaged by the

14

piston rod rollers when the cam tracks are in projected, operative positions for displacing each of the pistons toward the last mentioned rotor air passages on each revolution of the rotor, and 5 means responsive to an excess pressure of air in a storage container supplied by the air compressor for displacing said cam tracks away from the rotor to an inoperative position whereby the piston rods are not displaced toward the rotor when the storage container is fully charged to render the air compressor inoperative.

12. A rotary type air compressor as in claim 11, each of said cam tracks including a pair of arcuate sections having adjacently disposed hinged 15 ends which are displaceable toward and away from the rotor.

13. A rotary type air compressor as in claim 11, each of said cam tracks including a pair of reciprocally mounted plates disposed for sliding movement toward and away from one another and 20 spring urged toward one another, and an inverted V-shaped track element spring urged toward the rotor between the adjacent ends of said plates and forming the cam portion of the track 25 for displacing the plates away from one another, said cam track portions being displaced away from the rotor to an inoperative position by an excess air pressure in the storage container.

14. A rotary type air compressor comprising a 30 driven rotor, a turbine unit mounted on the periphery thereof including circumferentially spaced vanes having outer leading edges forming scoops adapted to draw air into turbine pockets formed between the adjacent vanes and for propelling the air inwardly toward the axis of the rotor, said rotor having an annular air chamber disposed inwardly of the turbine pockets into which the air is forced from the turbine unit and compressed, said rotor being provided with at 35 least one cylinder disposed between the axis thereof and said annular air chamber having a passage communicating with said air chamber through which air is forced under pressure for charging said cylinder with compressed air, a piston reciprocally mounted in said cylinder and spring urged toward one end thereof, cam means intermittently displacing the piston toward the opposite end of said cylinder, and an air conduit adapted to contain air under pressure including 40 a passage formed in the rotor and communicating with the last mentioned end of said cylinder through which air is forced under pressure when the piston is displaced by said cam means toward the last mentioned cylinder end.

ARTHUR C. EATON.
